WINDOW CONSTRUCTION

Harold E. Graves, Jr., Akron, Ohio, assignor to
 Brown-Graves Company, Akron, Ohio, a corporation of Ohio

Application May 12, 1950, Serial No. 161,526

4 Claims. (Cl. 20—70)

1

This invention relates to casement windows of the sliding hinge type.

In my prior Patents No. 1,973,565 and No. 2,051,638 I have shown windows of this type, and the present invention relates to improved features in the hardware employed on windows of the type shown in the said patents.

In the aforesaid windows the swinging sashes are easily inserted or removed by tilting the sash to engage or disengage upper and lower, pronged, spring clips which carry the hinges, and which clips engage in channels secured to the window frame. There is a tendency for rain water to collect in the lower one of these channels and, therefore, a central, run-off slot has been provided. It is one object of the invention to improve the hardware on the lower part of the sash, with especial reference to the drainage features. Another object is to simplify the manufacture and mounting of the hardware elements associated with the lower sash. Other objects are to improve the hardware in general, to give more positive engagement of the sash in its mounting, to provide a smoother, more certain action, and to protect the wood of a window sill against the effects of rain water.

These and other ends will be apparent to those skilled in the art, from the accompanying specification, as illustrated in the drawings, in which:

Fig. 1 is an elevational view, from the inside of a building, of the central part of a casement window sash in its frame, with parts broken away to show details of the hardware.

Fig. 2 is a sectional view, taken on the line 2—2 of Fig. 1.

Fig. 3 is a sectional view taken on the line 3—3 of Fig. 2.

Fig. 4 is a view similar to Fig. 3 showing the middle sash swung to open position.

Fig. 5 is a sectional view, taken on the line 5—5 of Fig. 3.

Fig. 6 is a sectional view, taken on the line 6—6 of Fig. 1.

Fig. 7 is an enlarged detail, in side elevation, showing the lower hardware assembly, which includes an attaching bar, a radius rod, a hinge pin and double leaf spring.

Fig. 8 is a sectional view, taken on the line 8—8 of Fig. 7.

Fig. 9 is a partial view, similar to the lower portion of Fig. 1, showing a modified construction.

Fig. 10 is a sectional view, taken on the line 10—10 of Fig. 9.

2

Fig. 11 is a sectional view, taken on the line 11—11 of Fig. 9, and

Fig. 12 is a view in perspective of one form of channel member.

5 In the drawings, the main window frame is indicated by the numeral 1, and the swinging casement by the numeral 2. In the structure illustrated, the swinging casement is flanked by two supplementary casements 3, which are permanently closed.

10 The swinging casement 2 is provided with facing strips 4 and 4', set in and fastened by screws 5 to the outer faces of the upper and lower rails, respectively, of the casement. Referring to the lower part of the casement, the facing strip 4 has, on the hinged end of the casement, an extension 6 which is bent downwardly, and again bent at its end 8 into parallelism with the lower edge of the casement. In the end 8 is secured, 15 as by riveting, a pin 9 having a head 11, and around the pin 9 is wrapped a two-pronged leaf spring 12 (Fig. 6) having a short arm 13 and a long arm 14, the arms being bent inwardly at their ends to facilitate sliding of the spring.

20 The leaf spring is slideable in a metal channel secured by a screw 15 in a groove 17 which is formed by routing the lower sill 18, the groove extending beyond the hinged end of the casement 2, as at 19, to accommodate the hinge pin 9, which is outboard with respect to casement 2.

25 The upright side walls 20, 21 of the channel extend from an end wall 22 at the inner end of groove extension 19 for a distance slightly beyond the center of the casement, at which location the bottom 23 of the channel is bent upward to provide a vertical wall 24 to the height of the channel and is then bent into parallelism with the bottom 23 of the channel, to form a facing plate 26. Beneath the latter is a strip of wood 27, 30 which serves as a backing, and both plate 26 and strip 27 are secured to the sill by a screw 15'. As most clearly seen in Fig. 12, the channel and facing strip are formed from a single piece of material.

35 Plate 26 and wooden strip 27 have aligned bores 28, 29, respectively, which receive, and anchor, a pin 31 which is secured in one end of a radius rod 32, the other end of which is pivoted to the central part of lower facing strip 4 of the casement, 40 by means of a rivet 33.

45 Plate 26 and wooden strip 27 have aligned bores 28, 29, respectively, which receive, and anchor, a pin 31 which is secured in one end of a radius rod 32, the other end of which is pivoted to the central part of lower facing strip 4 of the casement, 50 by means of a rivet 33.

A conventional latch 34 is provided on the free end of the casement 2 and it will be seen that as the casement is urged outwardly by a pressure on its latching end, the casement is constrained to turn about the rivet 33 and, as a consequence,

the hinge pins 9 move toward the center of the sill, along the channel. Upon closing, the action takes place in the reverse sense.

In this type of window, as constructed heretofore, the facing plate 26 and the channel have been separate members. This left the end of the wooden strip exposed. Also, the inner end of the channel was faced off on a diagonal, so that the outer upright wall 21 was shorter than the inner wall 20, and the bottom of the channel was diagonal at its end. This permitted run-off of rain water, but the top of the sill, at the outlet, was exposed to the effects of the water.

By the present construction, the outer wall 21 of the channel is also the shorter wall, but by the integral construction, the sill, at the run-off point for rain water, is covered by the channel bottom, this protective covering being extended to the outer edge of the sill by the tab 30 (Fig. 5) which is bent downward from wall 21 of the channel to provide the water exit. This feature, together with end 22 and riser 24 provide complete protection of all wooden surfaces on the sill top from the effects of rain water. Obviously, the various joints may be soldered or brazed. Furthermore, these advantages arise from the unitary structure of the channel and facing plate, which is, in itself, a desirable feature in the matters of manufacture and assembly.

The combined slide channel and face plate in the upper part of the window frame is identical with the lower one except that the cutting and bending of the tab 30 may be omitted, since the problem of water drainage is not present.

The hinges and leaf springs are somewhat different at the top and bottom of the casement. In all open positions of the casement, its weight is almost entirely carried by the sliding hinge and the radius link 32. To provide smooth sliding qualities, the weight at the hinge is carried by the head 11 of the hinge pin 9, the lower edges of leaf spring arms 13, 14 terminating above the head 11 for this purpose. Another reason for this offset is the fact that the axis of the hinge pins must be tilted in the act of inserting them in the channels. Downwardly bent extension 6 of the face plate 4 compensates for the thickness of radius link 32 and ensures that head 11 of the hinge pin rests on the bottom at all times.

Another consequence of the necessity for tilting the casement when inserting it in place is that the upper hinge pin does not contact the top of its receiving channel. Therefore, the extension 6' of the upper facing plate 4' is straight. Since the upper hinge pin must occupy a position somewhat downwardly of the top of its channel, the leaf spring arms 13', 14' are fashioned so that their top edges are flush with the top of pin head 11'. This ensures that the leaf spring arms lie within the channel to provide maximum surface contact therewith.

In Fig. 7 is shown an assembly of the unit comprising the facing plate for the casement, the radius link, and the sliding hinge. It will be noted that the radius link 32 has a natural, bowed form prior to mounting of the casement. This ensures retention of the pins 31 in the window frame and also minimizes friction between the radius link and the facing plate 5 to which it is pivoted. In order to increase the strength and permanence of the spring action of the bowed radius link, it is ribbed longitudinally at the time the bow is formed as at 36, so that its lateral cross-section has the form indicated in Fig. 8.

In Figs. 9 and 10 is shown a modification of the combined, channel and face plate wherein the wooden backing strip 27 may be eliminated. As best seen in Fig. 10, the facing portion 26 has integral, depending sides 37, 38 which serve to space it from the bottom of the groove in the sill, thus avoiding the need for the wooden spacer.

While certain preferred forms of the device have been shown and described, the invention is not limited thereby, since changes in the size, shape and arrangement, for instance, of various parts may be resorted to, without departing from the spirit or scope of the appended claims.

What is claimed is:

1. For use with a casement window of the sliding hinge type, a metal channel, and an extension on the bottom of said channel having a first portion bent athwart the ends of the channel walls, and a second portion bent into parallelism with the said bottom of the channel, one of said walls terminating short of said first portion, and the other of said walls in contact with said first portion.

2. For use with a casement window of the sliding hinge type, a metal channel, and an extension on the bottom of said channel having a first portion athwart the ends of the channel walls, and a second portion parallel to said bottom of the channel, and a tongue struck from one of said walls at the end thereof adjacent said first portion, and said tongue bent into parallelism with said bottom of the channel.

3. For use with a casement window of the sliding hinge type, a pair of longitudinally aligned channels, each inverted with respect to the other, an integral web connecting the bottoms of the channels, and one side wall of one of said channels having an opening near said web for water drainage from the bottom of said one of said channels.

4. For use with a casement window of the sliding hinge type, a pair of longitudinally aligned channels, each inverted with respect to the other, an integral web connecting the bottoms of said channels, one of the side walls of one of said channels terminating short of said web, to provide an opening, and a lateral extension of the bottom of said one of said channels providing an apron in front of said opening.
